(57) **CLAIM**

The ornamental design for a solar illuminated address number sign for a mailbox, as shown and described.

DESCRIPTION

FIG. 1 is a front, bottom perspective view of a solar illuminated address number sign for a mailbox, showing my new design;

FIG. 2 is a rear, top perspective view thereof;

FIG. 3 is a front elevational view thereof;

FIG. 4 is a left side elevational view thereof;

FIG. 5 is a right side elevational view thereof;

FIG. 6 is a right-side elevational view thereof;

FIG. 7 is a top plan view thereof;

FIG. 8 is a bottom plan view thereof;

FIG. 9 is an enlarged view of encircled portion labeled, "9," in FIG. 1; and,

FIG. 10 is an enlarged view of encircled portion labeled, "10," in FIG. 2.

The even dashed broken lines in the figures illustrate portions of the solar illuminated address number sign for a mailbox that form no part of the claimed design. The dot-dash-dot broken lines illustrate the boundary lines of the enlarged portion views of FIGS. 9 and 10 in FIGS. 1, 2, 9 and 10 and form no part of the claimed design.
